TIME TRIP DEVICE

Harry W. Harrison, Houston, Tex.; John C. Kinley, 1040 N. 6th St., Houston 36, Tex.; and Myron M. Kinley, Los Angeles, Calif., assignors, by direct and mesne assignments, to said John C. Kinley
 Filed Mar. 31, 1958, Ser. No. 724,962
 12 Claims. (Cl. 166—54.5)

This invention relates to time trip devices, and particularly to devices for providing a predetermined time delay in the operation of tools.

This application is a continuation-in-part of U.S. patent application Serial No. 681,526 filed September 3, 1957, now abandoned.

It is an object of this invention to provide a new and improved device for providing a time delay in the operation of a tool.

An important object of this invention is to provide a new and improved device for use in a well tool or the like, wherein an actuating means is provided for initiating the operation of such tool, and wherein chemical means are also provided for effecting the tripping or release of said actuating means after a predetermined period of time.

Another object of this invention is to provide a new and improved time trip device in a tool for cutting a flexible line in a well bore or the like, wherein said device includes means for tripping or releasing a lock for said tool after a period of time, and wherein such period of time is determined by the time for a chemical reaction within the tool.

A particular object of this invention is to provide a new and improved time trip device, wherein a locking pin is provided which is capable of being dissolved or severed by a liquid chemical after a predetermined period of time, and wherein means are provided for contacting said chemical with said pin to initiate the chemical action on said pin.

The preferred embodiment of this invention will be described hereinafter, together with other features thereof, and additional objects will become evident from such description.

The invention will be more readily understood from a reading of the following specification and by reference to the accompanying drawings forming a part thereof, wherein an example of the invention is shown, and wherein:

FIG. 1 is a view, partly in elevation and partly in section, illustrating the device of this invention in use in a tool for cutting flexible lines in a well bore or the like;

FIG. 2 is a sectional view taken on line 2—2 of FIG. 1 to illustrate the details of the time trip device of this invention;

FIG. 3 is a horizontal sectional view taken on line 3—3 of FIG. 5;

FIG. 4 is a vertical sectional view illustrating a portion of the structure shown in FIG. 2 after the liquid chemical has been released within the tool, but prior to the actual tripping of the device for actuating the tool therewith; and

FIG. 5 is a view similar to FIG. 2, but illustrating the device of this invention after the chemical action of the liquid on the locking pin has caused the tripping or release of an actuating means of the tool for initiating the operation of the tool with which the device of this invention is used;

FIG. 6 is a vertical sectional view of a modified time trip device; and

2

FIG. 7 is a horizontal sectional view taken on line 7—7 of FIG. 6.

In the drawings, the letter T designates generally a tool for cutting a wire line W or other flexible line. The tool T includes therewith the time trip device A (FIG. 2) of this invention, and such tool T is merely exemplary of various types of tools with which the time trip device A of this invention can be used. Briefly, the time trip device A includes a container 10 such as a glass bottle for a chemical in liquid form. The chemical is confined within the container 10 by a plug or closure member 11 and the container 10 is held in such closed position within the tubular body 12 of the device A of this invention, as will be explained more in detail hereinafter. 15 The liquid chemical within the container 10 is released therefrom by fracturing the container 10 as indicated in FIG. 4 of the drawings so that such chemical contacts a time delay element or locking pin 15, the purpose of which will be hereinafter explained more in detail. The chemical is of such nature that it dissolves or severs the pin 15 after it is in contact therewith for a predetermined length of time, and when such predetermined length of time elapses, the actuation of the tool T or any other tool with which the device A is associated is accomplished. 20 25 In the present form of the invention as illustrated in the drawings, the severing or dissolving of the pin 15 permits a spring 17 to move a plunger 18 downwardly for contact with a firing pin 19.

The firing pin 19 actually forms a part of the tool T for cutting the flexible line W, and such tool T is of the type illustrated in United States Patent 2,185,303 granted to M. M. Kinley. Such tool T includes a tubular body section 20 which is threaded or otherwise connected to the tubular body section 12 of the trip device A. Such body section 20 is illustrated as composed of several sections which are threaded together, but it will be appreciated that the entire body section 20 below the body section 12 (FIG. 1) may be formed in one piece if so desired. A plunger wedge 21 having an inclined or wedge surface 21a at its lower end is positioned within the lower part of the tubular body section 20 and it is held in the position shown in FIG. 1 by its contact with a gripper member 22. Such gripper member 22 is releasably retained in a slot 20a by a shear pin 23. When the plunger wedge 21 is forced downwardly with sufficient force, it applies a lateral force to the clamping member 22 to initially shear the pin 23 and then to move the member 22 outwardly in the groove 20a. Such action causes the clamping member 22 to move into gripping engagement with the flexible line or wire W. A cutter member 24, which is similar to the clamping member 22 is positioned below the member 22 and it is also held in a retracted position within a slot 20b of the body section 20 by a shear pin 25. After the member 22 has been moved into contact with the flexible wire W, the plunger wedge 21 can continue downwardly so that the wedge surface 21a can contact the end of the cutter member 24 to initially shear the pin 25 and then to move such cutter 25 in the slot 20b for severing the flexible wire W. It will be noted that the flexible wire W passes through a guide channel 26 so that the flexible wire W is confined within a relatively small tubular area to effect the proper gripping with the member 22 and the proper cutting with the cutter member 24.

For moving the plunger wedge 21 downwardly, an explosive cartridge 30 such as a shotgun shell is positioned above the wedge 21 for contact by the firing pin 19. Additional explosive powder may be incorporated below the cartridge 30 if so desired. In any event, upon the firing of the cartridge 30 by the downward driving action of the firing pin 19 against such cartridge 30, the explo-

sive force on the upper end of the wedge 21 drives it downwardly with sufficient force to shear the pin 23 and to drive the clamping member 22 into contact with the flexible wire W. The member 21 is continued in its downward movement by the force imparted from the explosion so as to also shear the pin 25 to move the cutter member 24 into contact with the wire W for cutting or severing same. A stop shoulder 20c at the lower end of the body section 20 limits the downward movement of the plunger wedge 21 so as to hold the wedge member 22 in its gripping or clamping contact with the wire W so that thereafter the wire W may be lifted to retract the tool T from the well with the portion of the wire W above the point at which it was cut by the member 24.

Considering the details of the time trip device A of this invention, as particularly illustrated in the drawings, such device A includes an upper head or adapter 35 which is threaded or otherwise connected to the body section 12 of the time trip device A. An annular seal 36 formed of rubber or similar material is provided between the head 35 and the tubular body section 12 to prevent fluid leakage, as will be more evident hereinafter. The upper part of the head or adapter 35 is provided with a hollow bore 35a which terminates in a lower annular shoulder 35b. The lower part of the head 35 is threaded at 35c for receiving a bolt or screw 38 in threaded engagement therewith. The screw head 38a is preferably an "Allen" head which is longitudinally movable within the bore 35a as the screw 38 is threaded in its threaded engagement with the threads 35c. A suitable screwdriver or other tool is adapted to be inserted within the bore 35a for engaging the screw head 38a to turn such screw 38 relative to the head 35. The lower end of the screw 38 is in contact with a sliding stop member 40 which is preferably substantially cylindrical and which is formed with a reduced diameter portion 40a so as to provide a lower annular lateral shoulder 40b against which the spring 17 contacts. Preferably, the screw 38 is not connected with the stop member 40 so that relative rotation between the screw 38 and the member 40 is permitted while effecting a downward movement of the member 40 as the screw 38 is rotated or turned. Thus, in the preferred form of the invention, the lower end 38b of the screw 38 is tapered or pointed so as to fit within a correspondingly tapered or pointed recess 40c in the upper surface of the stop member 40.

The spring 17 is ordinarily a coil spring and it is positioned with its lower end resting upon the upper surface of a flange 42 formed on the upper end of the plunger 18. Such flange 42 may be formed in numerous ways so long as space is provided between its outer edge and the internal surface of the bore 12a of the tubular body section 12 to permit liquid to flow therebetween. Thus, as illustrated in particular in FIG. 3 of the drawings, the flange 42 is formed with flat sides 42a which are spaced from the bore 12a for the flow of the liquid in the container 10 to the area below the flange 42 when such container 10 is broken or opened, as will be more evident hereinafter. A sharp point or fracturing projection 42b is preferably provided on the upper surface of the flange 42 for contact with the bottom of the frangible container 10 to assist in initiating the cracking or breaking of such container 10 to effect the release of the liquid chemical therein.

The plunger 18 is locked or held in the raised position illustrated in FIG. 2 by the lock pin 15. Such pin 15 rests upon an annular lateral shoulder 12b which forms the lower end of the bore 12a. The plunger 18 is ordinarily formed of metal and it is provided with an opening 18a therethrough for receiving the pin 15 which is usually made of a different material so that it is capable of being dissolved or severed by chemical reaction with the liquid in the container 10 after it is released therefrom and caused to contact such pin 15. The particular material of which the pin 15 is made will depend upon

the liquid which is used for dissolving or chemically reacting therewith to sever or weaken same sufficiently for fracturing the pin 15 to permit the downward movement of the plunger 18 relative to the body section 12.

5 As an example of materials for the pin 15, an acrylic resin or a polyvinyl acetate resin may be used, and in such case a solvent such as acetone, methyl acetate, ethylene dichloride, monomeric methyl methacrylate, or benzo peroxide, would be used as the liquid in the container 10 for contacting the pin 15 when desired. Other materials for the pin 15 and other liquids capable of chemically reacting with such pins 15 will occur to those skilled in the art and the invention is not limited to the particular materials given as an example.

15 The plunger 18 extends below the shoulder 12b into a reduced diameter bore 12c of the body section 12. A seal ring 45 formed of rubber or other similar sealing material is preferably mounted on the plunger 18 for sealing contact with the reduced diameter bore 12c to prevent fluid flow between the plunger 18 and the bore 12c. To be certain that the lower end 18b of the plunger 18 contacts the upper end of the firing pin 19 with sufficient force to fire the cartridge 30, the air in the bore 12c below the lower end 18b of the plunger 18 is permitted to escape through a relief hole 18c. Such relief hole 18c extends upwardly from the lower plunger end 18b for the full length of the plunger 18 (FIG. 2) and connects with a lateral relief hole 42c (FIGS. 2 and 3) in the flange 42 so as to establish communication from the area of the bore 12c below the seal 45 to the area of the bore 12a which is above the seal 45. It should be noted from FIG. 3 that the longitudinal hole or passage 18c is displaced to one side of the opening 18a which is provided for the rod 15 so that there is no communication between the hole 18c and the opening 18a. However, if desired, the hole 18c may intersect with the opening 18a, in which case the hole 18c would be shortened so that it would only extend from the end 18b, or some other point below the seal 45, to the opening 18a. The portion of the hole 18c and the hole 42c could be omitted with such a modification.

If the hole 18c is formed as shown in the drawings and communicates with the hole 42c, it is desirable to provide a removable plug 50 formed of cork, rubber or other similar material. Such plug 50 is inserted into the outer end of the hole 42c to close same for preventing liquid from the container 10 from flowing downwardly through the relief holes 42c and 18c. Ordinarily, the level of the liquid in the bore 12a is below the flange 42

50 so that a chemical reaction between such liquid and the plug 50 does not occur. If such a chemical reaction should be desired, however, the lateral hole 42c could be located in the plunger 18 below the liquid level assumed in the bore 12a after such liquid is released from the container 10. In the event the structure is modified 55 as proposed above to form the hole 18c so as to intersect with the opening 18a, the rod 15 would serve as a plug until it was severed or sufficiently dissolved to permit liquid to flow around the rod 15 in the opening 18a to the hole 18c. The sealing between the rod 15 and the walls 60 of the opening 18a would normally prevent the liquid flow until the rod 15 is severed. It should be noted that in this form of the invention illustrated in the drawings, the upper end of the firing pin 19 extends into the lower portion of the reduced diameter bore 12c so that when 65 the pin 15 is severed or fractured so as to permit the plunger 18 to move downwardly, the lower end of the plunger 18 can move into contact with the firing pin 19 for effecting the firing of the cartridge 30. It should also be noted that the pin 15 retains the flange 42 at a sufficient elevation within the bore 12a so that the spring 17 is confined between the flange 42 and the lateral surface 40b of the stop member 40 in a compressed condition.

70 Therefore, when the pin 15 is released by the chemical action with the liquid in the container 10, the spring 17 forces the plunger 18 downwardly to contact 75

its lower end with the firing pin 19. Also, further compression of the spring 17 is accomplished during the lowering of the stop member 40 for fracturing the container 10 to release the chemical therein. Such additional compression of the spring 17 is also utilized in the downward movement of the plunger 18 for contacting the firing pin 19.

In the operation or use of the time trip device A of this invention in the cutting tool T as illustrated in the drawings, the tool T is initially positioned on a flexible wire W at the surface of a well. In well operations, various well tools are lowered on a flexible line such as the wire line W illustrated in the drawings and, in some instances, such tool at the lower end of the flexible line W may become lodged or caught in the well bore so that it is impossible to retrieve it by pulling upwardly on the wire line. In such case, it becomes necessary to sever the line at some inaccessible point within the well bore so that the wire line may be salvaged and so that some other type of fishing tool may be inserted to recover the tool or equipment which was lowered originally on the flexible line W. Thus, assuming the wire W is in a well bore and is connected with a tool or piece of equipment in the well bore which is lodged or caught so that it cannot be retrieved with the wire line W, then the tool T illustrated in the drawings would be used. The tool T would be inserted over the upper end of the wire W at the earth's surface, usually in the vicinity of the well derrick, so that the wire line or other flexible line W extends through the guide sleeve 26 as shown in FIG. 1 of the drawings. The tool T is then in a position for dropping or lowering within the well bore or pipe by gravity until it reaches the upper end of the tool connected at the lower end of the wire line W.

With the time trip device A of this invention, a screwdriver or other tool is positioned within the bore 35a for turning or rotating the screw 38 either just prior to or just after the positioning of the tool T on the line W. The rotation of the screw 38 causes the stop member 40 to move downwardly relative to the tubular body section 12. Since the lower end of the container or bottle 10 is resting upon the flange 42, the downward movement of the stop member 40 imparts a compressive force to the container 10 and such compressive force ultimately becomes sufficient to fracture the container 10. As previously stated, the container 10 is preferably made of glass or other similar frangible material. The container 10 has liquid or chemical therein and since the container 10 is securely held in a position shown in FIG. 2 between the member 40 and the flange 42 prior to the fracture thereof, the release of such liquid is prevented until the container 10 is fractured or broken. The fractured container 10 is illustrated in FIG. 4. The liquid flows from the fractured bottle 10 downwardly past the flange 42 due to the fact that the spaces between the flange 42 and the bore 12a are provided by the flat spaced surfaces 42a of the flange 42. The chemical in liquid form thus collects in the bore 12a in contact with the rod or pin 15. The seal 45 prevents the fluid from flowing downwardly and out of the chamber provided thereabove within the tubing section or body section 12. The seal 36 at the upper end of the body section 12 also prevents the escape of the liquid from the interior of the section 12 in the event the tool is shaken or inverted after the liquid is released from the container 10. The liquid which is released from the container 10 is capable of dissolving or etching the pin or rod 15, and a partially dissolved rod is illustrated in FIG. 4. The rod or pin 15 ultimately becomes sufficiently weakened so that the spring force applied thereto by the spring 17 effects a shearing or severing of the rod or pin 15. As previously mentioned, the spring 17 is placed under additional compression when the screw 38 is rotated for breaking or fracturing the container 10. The force of the spring 17 is then relatively great and it applies a continuous downward force to the pin 15 which is normally insufficient

to fracture the pin 15, but when the pin 15 has been subjected to the chemical action by the released liquid within the section 12, then the spring force 17 is sufficient to fracture or shear the pin or rod 15.

The strength of the solution of the liquid in the container 10 and the size of the rod 15 can be controlled in accordance with the time delay which is desired prior to the movement of the plunger 18 downwardly. Of course, the rod 15 must be at least of sufficient strength to resist fracture during the initial breaking of the glass or frangible container 10, but it may vary in thickness from such minimum thickness so that greater lengths of time or lesser lengths of time before the chemical liquid reacts with the pin 15 can be obtained prior to the shearing or severing of the pin or rod 15. The time delay is desirable in connection with the cutter tool T illustrated in the drawings in order to permit the tool T with the time trip device A to fall from the ground level down into the well bore the full length of the flexible line or wire W. As is well known, wells are of extremely great depths in many instances and it therefore requires a considerable amount of time for a tool such as the cutter tool T to reach the bottom of the wire W in contact with the upper end of the tool connected with such wire W. During the descent of the tool T the liquid or chemical is reacting with the rod or pin 15 so that after the tool T has reached its lowermost position at which it is desired to cut the wire line W, the tool is actuated for effecting the clamping and cutting of the wire line W.

Thus, after the screw 38 is manipulated at the surface of the well or the ground level to release the chemical or liquid from the container 10, the entire tool T is dropped by gravity so that it slides downwardly along the wire line W. The predetermined length of time that it takes for the liquid to react with the rod or pin 15 in order to sever or shear same is always sufficient to permit the tool T to fall into contact with the tool or equipment attached at the lower end of the wire W, and preferably there is sufficient time delay after the tool T reaches the lower end of the wire W before the tool T is actuated so that premature actuation of the tool T and therefore premature cutting of the wire line W is prevented.

When the tool T has reached the tool or equipment at the lower end of the wire line W and is therefore halted in its descent on the wire line W, the tool T remains in that position until such time as the acid or other liquid sufficiently dissolves or reacts with the rod or pin 15 to enable the spring 17 to impart the downward shearing force to the pin 15 for shearing or severing same.

When the shearing of the pin is accomplished by the chemical reaction, the spring 17 forces the plunger 18 downwardly into contact with the upper end of the firing pin 19 so as to fire the cartridge 30 and the explosive powder therewith. As the plunger 18 moves downwardly, the air in the bore 12c below the seal ring 45 is gradually compressed unless such air leaks upwardly past the seal ring 45. If such compression occurs, the plug 50 is forced out of the hole 42c to thereafter permit the flow of the air upwardly through the holes 18c to 42c to thereby relieve the pressure which would otherwise develop in the bore 12c below the plunger 18. By so relieving such pressure, the full force of the spring 17 is transmitted from the plunger 18 to the firing pin 19 to be certain that a sufficient impact is imparted to the firing pin 19 to fire the cartridge 30 and the explosive powder. It will be understood that if the hole 18c intersects with the opening 18a in the modification as proposed above, the air below the plunger 18 will escape or be relieved through the hole 18c and opening 18a as the plunger 18 is forced downwardly by the spring 17. In any event, the explosion of the powder causes the wedge 21 to move downwardly so that the wedge 21

first applies a sufficient force to the clamping member 22 to shear the pin 23 and then the wedge 21 forces the member 22 out into gripping engagement with the wire W. The downward movement of the wedge member 21 is continued by the explosive force acting thereon so that the pin 25 is next sheared and the cutter member 24 is forced outwardly to sever or cut the wire W. The downward movement of the wedge member 21 is preferably halted by its contact with the shoulder 20c or other stop surface so that the cylindrical portion of the member 21 holds the clamping member 23 in gripping engagement with the wire W. Thereafter, the complete tool T can be lifted by raising the flexible line or wire W at the surface of the well, so that the wire W is recovered and the tool T is also recovered.

In FIGS. 6 and 7, a modified construction is illustrated wherein the time trip device A' is utilized instead of the time trip device A of FIGS. 1-5 with a tool such as the cutting tool T. The tool A' includes a sleeve housing or tubular body 112 which corresponds with the body 12 of FIG. 2 and which also is adapted to connect with the upper end of the housing or body section 20 of the cutting tool T in the event such time trip device A' is used therewith. It will be understood of course that when the time trip device A' is used with the tool T, the time trip device A is not used.

The time trip device A' has a tubular head 135 connected to the upper end of the body or housing 112 in the same manner as the head 135 is connected with the body 12. An annular seal or O-ring 136 of rubber or other similar sealing material is provided to prevent fluid flow at the connection between the body 112 and the head 135 (FIG. 6). An operating screw 138 corresponding to screw 38 in FIG. 2 is threaded in engagement with internal threads 135c so that by engaging the head 135a of the screw 138, such screw 138 may be moved upwardly or downwardly as desired. A substantially cylindrical block 140 is mounted below the screw 138 in the same manner as the block 40 in FIG. 2. Such block contacts a plug or closure member 111 which serves to close the upper end of a bottle or container 110. The lower end of the bottle 110 rests upon a fixed support 118 which has a relatively sharp point 118a in engagement with the lower surface of the bottle or container 110. Such support 118 is an integral part of the body 112, or is fixed thereto in any desired manner so that the bottle 110 is held firmly between the fixed support 118 and the block 140 when the screw 138 is turned downwardly a sufficient amount. Also, when desired, as will be more fully explained, the bottle or container 110 is fractured or broken to release the contents thereof by applying a sufficient downward force on the bottle or container 110 with the rotation of the screw 138 in a downward direction.

A plurality of openings or channels extend downwardly from the main chamber 112a of the housing 112 and such openings are identified with the numeral 112b. Such openings or channels 112b provide for the flow of the liquid from the container 110 after it has been released therefrom to the chamber 112c at the lower portion of the body 112. Prior to the release of the liquid from the bottle or container 110 by the fracturing thereof, the openings or channels 112b are maintained closed with a plate 115 which is annular in shape in the form illustrated in FIG. 6 of the drawings. Such plate 115 is formed of a material which is capable of being dissolved or severed by chemical reaction with the liquid which is released from the bottle or container 110. Therefore, the time required for the dissolving or severing of the plate 115 after the contents of the bottle or container 110 has been released into the chamber 112a is the time required for the contents or liquid from the bottle or container 110 to pass through the plate 115 and downwardly into the chamber 112c. The chamber 112c has

material 95 therein which is capable of chemically reacting with the liquid which is released from the container 110 so as to cause an explosive force. In the preferred form of the invention therefore, the contents of the bottle or container 110 is picric acid and the material 95 is sulfuric acid in liquid form, and the plate 115 is copper. So long as the picric acid and the sulfuric acid are separated from each other, there is no danger of an explosion occurring from such materials, but when they react with each other, they react sufficiently violently to create an explosive force which is utilized in connection with this invention, as will be explained.

The material 95 is confined within the chamber 112c by a plate or diaphragm 96 so as to separate such material 95 from the explosive powder charge 130 positioned therebelow. Such charge 130 is positioned at the upper end of the wedge 21 which is ordinarily constructed in the same manner as the wedge 21 of FIG. 1 of the drawings. The explosive powder charge 130 takes the place of the powder charge 30 illustrated in FIG. 1. Therefore, when the picric acid has dissolved the copper and has passed into contact with the sulfuric acid, they chemically react to create the initial explosion and such explosion is sufficient to fracture or blow the diaphragm 96 downwardly to ignite and explode the powder charge 130. The explosive force created by the powder charge 130 then drives the wedge 21 downwardly relative to the body 20 in the same manner as previously described in connection with the form of the invention shown in FIGS. 1-5.

The operation of the form of the invention shown in FIGS. 6 and 7 is believed evident from the foregoing description. The time trip device A' is mounted on a tool such as the line cutting tool T of FIG. 1 in place of the time trip device A illustrated therein. Under such circumstances, the screw 138 is turned with a screw driver or other tool at the surface of the well prior to the lowering of the tool T on the flexible wire line W so that the liquid or contents of the container 110 is released. The liquid within the container 110, when so released, is of such a nature that it can dissolve or otherwise sever the plate 115. The plate 115 can be metal or it can be formed of the materials referred to above in connection with the lock pin 15 so long as such material is capable of being dissolved or severed by the particular liquid which is within the container 110 when it is released therefrom. The thickness of the material 115 and the nature thereof with respect to the liquid in the container 110 will determine the time delay provided by this time trip device A'. When the acid or other liquid has dissolved or severed the plate 115 sufficiently to permit the passage of the liquid through the openings 112b to the chamber 112c, the liquid comes into contact with the material 95 for creating the explosive force. Such explosive force detonates the powder charge 130 for moving the mandrel 21 downwardly as explained in connection with FIG. 1. When the wire line W has been severed and gripped as explained in connection with FIG. 1, then the complete tool with the time trip device A' thereon may be removed from the well by lifting the wire line W upwardly.

It can thus be seen that with the time trip devices A and A' of this invention, it is unnecessary to drop any weights in a well to actuate the tool T and any other manipulation of the wire W is unnecessary. The chemical is contained within the containers 10 and 110 and is safe from injurious contact or disturbance during the transportation thereof to a place for use and during storage. Also, prior to the actual time that such chemical is to be used, the chemical is prevented from being inadvertently released from its container 10 or 110 because such containers 10 and 110 are fractured only by the positive movement of the screws 38 and 138 downwardly, which requires the turning of such screws 38 and 138 with a screwdriver or other tool.

Although the time trip devices A and A' are particularly desirable and useful in connection with the cutter tool T, as explained above, they are also useable in connection with any other type of tool wherein it is desired to delay the actuation thereof for a predetermined length of time.

The foregoing disclosure and description of the invention is illustrative and explanatory thereof and various changes in the size, shape and materials, as well as in the details of the illustrated construction, may be made within the scope of the appended claims without departing from the spirit of the invention.

What is claimed is:

1. A time trip device comprising, a tubular body, a plunger longitudinally movable in said body, a lock pin for normally preventing longitudinal movement of said plunger in one direction relative to said body, a container positioned on said plunger for holding a chemical therein capable of reacting with said lock pin for effecting a release thereof, means for releasing the chemical in the container therefrom for contact with said lock pin, and means for applying a longitudinal force to said plunger after said pin is sufficiently weakened for severing same.

2. A time trip device comprising, a tubular body having a chamber therein with a longitudinal opening therebelow, a plunger extending into the lower end of said chamber and longitudinally movable in said longitudinal opening, a seal ring on said plunger in sealing engagement with the wall of said longitudinal opening for maintaining a seal at the lower end of said chamber at all times, a lock pin for normally preventing longitudinal movement of said plunger in one direction relative to said body, resilient means for urging said plunger in said one direction which is normally insufficient to sever said lock pin, means within said tubular body for weakening said lock pin within a predetermined period of time so that the force applied to said plunger and lock pin is then sufficient to sever said lock pin to move said plunger in said one direction.

3. The structure set forth in claim 2, including means for increasing the force applied by said resilient means at the beginning of said predetermined period of time.

4. The structure set forth in claim 2, wherein said lock pin is made of an acrylic resin, and wherein said means for weakening said lock pin is a liquid chemical capable of reacting with said acrylic resin to dissolve same at a portion thereof for weakening same.

5. In a tool for severing a flexible line in a well or the like having cutter means for severing the flexible line and explosive means for moving said cutter means into cutting engagement with said flexible line, the improvement residing in a time trip device comprising, a tubular housing having a chamber therein, a container in said chamber and separate therefrom for confining a chemical in said housing for handling therewith without danger of losing or releasing same prematurely, a support means in said housing for supporting said container, a movable head engageable with the upper end of said container for squeezing said container between said head and said support for releasing said chemical in said housing, and means capable of reacting with said chemical after its release in the housing for initiating a detonation of the explosive means after a predetermined period of time.

6. The structure set forth in claim 5, wherein said last-named means comprises a lock pin.

7. The structure set forth in claim 5, wherein said last-named means comprises a closure plate.

8. A time trip device comprising, a tubular body having a chamber formed in the bore thereof, a support in

5 said chamber adapted to move longitudinally relative to said body, a frangible container for confining a chemical therein within said chamber and positioned on said support, a movable head in engagement with the upper end of said container to hold said container between said head and said support, a time delay element within said chamber and connected to said support for preventing longitudinal movement of said support and adapted to be contacted by the chemical from said container when said container is fractured for releasing said support for longitudinal movement, a resilient member extending from said support to said movable head and surrounding said container, and actuating means for moving said movable head relative to said support to squeeze said container for fracturing same and for compressing said resilient member, whereby said chemical is released so that after said time delay element is acted upon by said chemical said support is longitudinally moved in said body by said resilient member.

10 9. The structure set forth in claim 8, wherein said actuating means is positioned in the bore of said tubular body and is accessible from the exterior thereof.

15 10. The structure set forth in claim 2, wherein said plunger has a relief port for preventing a fluid lock when said plunger moves longitudinally in said opening.

20 11. A time trip device comprising, a tubular body having a chamber formed therein, a plunger longitudinally movable in said body, a frangible container supported on said plunger and having a chemical therein adapted to be released upon a fracturing thereof, a lock pin for normally preventing longitudinal movement of said plunger in one direction relative to said body, means for fracturing said container to contact said lock pin with the chemical from said container for reacting therewith for weakening said pin sufficiently for severing same to release the plunger from the body for longitudinal movement relative thereto in said one direction after the predetermined time required for such chemical reaction, and means for applying a longitudinal force to said plunger in said one direction which is insufficient to normally sever said lock pin but which is sufficient to sever said lock pin after it has been weakened by said chemical reaction.

25 12. A time trip device comprising, a tubular body having a chamber formed therein, a plunger longitudinally movable in said body, a frangible container supported on said plunger and having a chemical therein adapted to be released upon a fracturing thereof, a lock pin for normally preventing longitudinal movement of said plunger in one direction relative to said body, means for fracturing said container to contact said lock pin with the chemical from said container for reacting therewith for weakening said pin sufficiently for severing same to release the plunger from the body for longitudinal movement relative thereto in said one direction after the predetermined time required for such chemical reaction, and a spring for applying a longitudinal force to said plunger in said one direction which is insufficient to normally sever said lock pin but which is sufficient to sever said lock pin after it has been weakened by said chemical reaction.
